CARL OTTO, OF ESSEN-ON-THE-RUHR, GERMANY.

COKE OVEN AND PROCESS OF OPERATING SAME.

Application filed December 10, 1925, Serial No. 74,444, and in Germany September 25, 1924.

This invention relates to continuously operated coke ovens having vertical coke chambers.

With ovens of this kind the coal to be distilled has hitherto been caused to uniformly glide down and to be withdrawn by means of conveying drums or worms. The cooling of the coke and the production of water gas is effected by steam supplied under constant pressure to the coke chambers. Owing to the dense structure of the coke cake formed during distillation of the coal and sinking down in the chamber as a closed baked mass, however, the outer surface only of the coke cake comes into contact with the supplied steam and the production of water gas takes place in a correspondingly small degree. In order to enable it to be emptied through the withdrawing openings, the coke cake has further to be crushed by the withdrawing mechanism.

The invention has for its object to obviate this drawback. According to the invention the coke cake is loosened within the coke chamber by a useful method of withdrawing it from this chamber so that it is deprived of its dense structure. The loosened coke thus offers the largest possible contact surface for the production of water gas; the loosening of the coke further enables it to be withdrawn from the lower openings, without any mechanism; the production of steam, finally, and the formation of water gas, if desired, is regulated automatically in accordance with the temperature of the coke at the level of the water mantle.

In order to allow the invention to be more readily understood, a preferred embodiment of the subject matter thereof is illustrated in the accompanying drawing which forms part of this specification.

Fig. 1 is a vertical section of the oven chamber and the parts connected therewith, and

Fig. 2 is a sectional detail of the steam pipe supplying system.

Fig. 3 is a horizontal cross section on line 3—3 of Fig. 1.

1 denotes the vertical and tapered coking chamber, enlarged towards its base and the refractory walls 2 of which are heated indirectly in the usual manner. Below the chamber 1 is arranged a prolongation 3 which serves as a coke receptacle and is subdivided by a partition 4 so as to form two or more individual compartments 5. The

partition 4 terminates at its lower end into a hollow tapered cup 6 situated at a small distance above a base-plate 7. Adjacent to this base-plate are emptying openings for the compartments, each provided with a flap 8, the number of which openings depends on that of the compartments 5. For the sake of clearness only two compartments 5 are shown.

The above-described oven works as follows:

A determined quantity of coke is withdrawn through one of the flaps 8 into the receptacle 30. By this withdrawal the coke in the one half of the chamber 1 is set in motion and loosened by the upper coke layers slipping down so that the lower, enlarged space of the chamber 1 is completely filled by the loosened coke. After the said flap 8 has been closed again, an equal quantity of coke is withdrawn by opening the second flap 8.

Owing to this selective withdrawal the coke is so loosened within the chamber 1 that it completely fills the enlarged lower portion thereof. Owing to this slipping down of the coke, it enters the range of the upper portion of the prolongation 3 which is constructed as a water jacket 11 and at the same time serves as a steam generator. Fresh coal will correspondingly follow into the chamber 1 from the feed tank 9 into which it is supplied from a charging hopper 10.

A larger quantity of steam is immediately required in order to cool the coke which has slipped down, as described. This steam is delivered automatically by the water jacket or steam generator 11 and streams through a steam collector 12 and pipe 13 into the space 14 situated between the cup 6 and the steam deflecting base-plate 7 from where the steam is spread out uniformly into the individual compartments 5, whereby a very quick and uniform cooling of the coke is attained. The steam is superheated by this cooling operation and will find a very large contact surface in the loosened hot coke layers filling the lower portion of the chamber 1 so that it is here decomposed into water gas. The water gas thus generated escapes together with the gases of distillation through collecting pipe 15 into the hydraulic main 16 mounted on the super-structure 17 of the oven.

In some cases it will be preferable to not cool the coke in the receptacle 3 by water

gas, but by another gas. To this end the gas of distillation produced by the coking operation as well as any desired foreign gas may be made use of, for instance generator gas or waste combustion gas. In using such gases the advantage is offered that these gases produce, in the lower portion of the chamber, the desired cooling action, while they will exert a drying effect upon the fed fresh coal in the upper portion of said chamber, this being an important advantage particularly in case coal containing a comparatively large quantity of water is to be distilled.

15 The gases of distillation produced by the coking operation may be introduced in the receptacle 3, as mentioned, by a pipe 18 branched off from the collecting pipe 15, pipe 18 being connected to pipe 13, as shown in the drawing. If foreign gases are used as cooling media, these gases are supplied to the receptacle 3 through a short pipe 19 likewise connected to pipe 13. In such a case the steam from the collector 11, the 25 gases from the collecting pipe 15 and the foreign gases supplied by pipe 19 may be used selectively or in common as cooling mediums. Valves 20, 21, 22 serve in the usual way for cutting off the individual 30 pipes.

Having now particularly described and ascertained the nature of this invention and in what manner the same is to be performed, it will be understood, the changes usual to 35 those skilled in the art may be made in carrying the invention into effect without departing from its principle, I declare that what I claim is:—

1. A coke oven having a vertical coke 40 chamber having heating walls and provided with a prolongation situated below said chamber, a partition in said prolongation so as to form a plurality of individual compartments, each of said compartments having an emptying opening and means for closing 45 said openings.

2. A coke oven having a vertical coke 50 chamber, provided with a prolongation situated below said chamber, a partition in said prolongation so as to form a plurality of individual compartments, said partition terminating in a hollow cup, a base-plate arranged below said cup, said base-plate having adjacent thereto emptying openings, one 55 for each compartment, and means for closing said openings.

3. A coke oven having a vertical coke 60 chamber having heating walls and provided with a prolongation situated below said chamber, a water jacket arranged around the upper portion of said prolongation, a partition in said prolongation so as to form a plurality of individual compartments, means 65 for supplying steam from said water jacket to said compartments, each of said compart-

ments provided with an emptying opening and means for closing said openings.

4. A coke oven having a vertical coke chamber, provided with a prolongation situated below said chamber, a water jacket arranged around the upper portion of said prolongation, a partition in said prolongation so as to form a plurality of individual compartments, a steam collector, a pipe connection between said water jacket and said steam collector, a pipe connection between said steam collector and the interior of said prolongation, said compartments having each an emptying opening, and means for closing said openings.

5. A coke oven having a vertical coke chamber provided with a prolongation situated below said chamber, a partition in said prolongation so as to form a plurality of individual compartments, said partition terminating in a hollow cup, a base-plate arranged below said cup, said base-plate having adjacent thereto emptying openings corresponding in number to said compartments, means for closing said openings, a water jacket arranged around the upper portion of said prolongation, a steam collector, a pipe connection between said water jacket and said steam collector, and a pipe connecting the space situated between said base-plate and said cup, with said steam collector.

6. A coke oven having a vertical coke chamber provided with a prolongation situated below said chamber, a partition in said prolongation so as to form a plurality of individual compartments, said partition terminating in a hollow cup, a base-plate arranged below said cup, said base-plate having adjacent thereto, emptying openings corresponding in number to said compartments, means for closing said openings, a water jacket arranged around the upper portion of said prolongation, a steam collector, a pipe connection between said water jacket and said steam collector, a pipe connecting the steam collector with the space between said base-plate and said cup, means for cutting off said last-named pipe connection, a collecting pipe on said coking chamber for the gases of distillation, a branch pipe connecting said collecting pipe and said pipe connecting the space between said base-plate and said cup with the steam collector, a connecting branch on said last-named pipe for supplying foreign gases, means for cutting off said foreign gaspipe and means for cutting off said connecting branch and said branch pipe.

7. The process of discharging coke from a vertical coke oven having a prolongation 125 provided with emptying openings at the bottom of the prolongation of the oven chamber, and with closures for said openings, which consists in successively opening the said emptying openings and successively 130

discharging the coke therethrough by gravity, whereby the structure of the coke filling said prolongation and in said chamber is loosened.

- 5 8. The process of producing and cooling hot coke in a vertical coke oven provided with heating walls and a depending prolongation, forming a coke receiving chamber below the heating walls, said prolongation 10 surrounded by a water jacket, which consists in producing hot coke in said oven and sup-

plying said coke while still hot to said prolongation so as to generate steam from the water in said jacket, supplying the steam generated in said water jacket by the hot 15 coke into the interior of the prolongation, thereby cooling the coke, the quantity of supplied steam increasing with the temperature of the coke filling said prolongation.

In testimony whereof, I have signed my 20 name to this specification.

CARL OTTO.
